UNITED STATES PATENT OFFICE.

JAMES WOOLWORTH AND WILBER F. COWLES, OF ST. MARY'S, OHIO.

WOOD STIRRUP.

SPECIFICATION forming part of Letters Patent No. 267,961, dated November 21, 1882.

Application filed September 23, 1882. (No model.)

To all whom it may concern:

Be it known that we, JAMES WOOLWORTH and WILBER F. COWLES, of St. Mary's, in the county of Auglaize and State of Ohio, have 5 invented a new and useful Improvement in Wood Stirrups, of which the following is a full, clear, and exact description.

Our improvements relate to the construction of wooden stirrups, in which the body of the 10 stirrup is formed by bending a slat to the required shape and the ends connected by a roller or neck-block.

Heretofore in the manufacture of these stirrups, in order to use a roller having square 15 ends, the slat has been formed with an offset at each end, so that when bent up the ends were of the required shape to receive a square-ended roller; but in this form of stirrup, the 20 slat being cut at the ends diagonally of the grain of the wood, the stirrup was weakened at the point where the most strength was required.

The object of our invention is to construct 25 these stirrups so that they shall be equally as strong at the neck or bend as in any other part of the slat, and also to provide for the easy bending of the slats, so that a good shape can be given to the body of the stirrup.

To these ends our invention consists of a 30 slat bent into the desired shape and slotted in the direction of the grain of the wood, said slat being bent at its upper ends vertically where the roller or connecting cross-piece is connected thereto, substantially as hereinafter 35 more fully set forth and claimed.

Reference is to be had to the accompanying 40 drawings, forming a part of this specification, in which similar letters of reference indicate corresponding parts in all the figures.

Figure 1 is an edge view of one of the slats 45 from which a stirrup is to be formed after being cut and previous to bending. Fig. 2 represents a similar slat with the saw-kerfs differently arranged. Figs. 3 and 4 are side views of a complete stirrup. Fig. 5 is an end view of the same.

A in Figs. 3, 4, and 5 is a complete stirrup, the body portion of which is formed of the 50 bent slat *a*, having its ends connected by the roller or neck-block *b*. The ends of the slat *a* against which the ends of the roller *b* take are bent outward, so that a roller having straight ends may be used, and the roller is attached in the usual manner by bolts *c*, pass-

ing through it and the ends of the slat. In 55 the manufacture of the stirrups the slats *a* are first cut out, of suitable width and thickness, and with the ends tapering in the usual manner in order to give the proper shape to the sides of the stirrup, as shown in Fig. 5. Saw- 60 cuts, as shown at *d d*, Figs. 1 and 2, are then made in the ends of the slats. In Fig. 1 these are shown as extending nearly to the middle or the slat, so that they allow of the slat being formed with the main bends at the bottom, 65 and also with the bends at the ends.

Fig. 4 shows a complete stirrup made from a slat similar to the one shown in Fig. 1. In Fig. 2 the cuts *d* extend only a short distance from the ends, or just far enough to allow of 70 the bend to accommodate the roller. In order to form the main bend, the slat is made with saw-kerfs *e*, and these cuts we make of the **V** form shown, or widest at their outer ends, which allows of the ready bending of the slat 75 to the form required; and it will be seen that the pieces between the saw-cuts being of dove-tail form, or wider at the inner portion, it is impossible for the pieces to become loose and fall out, as is usually the case when the saw- 80 cuts are made of uniform width.

Fig. 3 shows a stirrup made from the slat shown in Fig. 2.

By this construction we are enabled to give 85 the proper bend to the stirrup at the neck to receive a square-ended roller without weakening the stirrup. At the same time less material is required than in the ordinary stirrup, in which there is necessarily a waste in order to form the offset at the side.

It will be understood that we lay no claim 90 in this application to the stirrup shown in Fig. 3 of the drawings.

Having thus described our invention, we 95 claim as new and desire to secure by Letters Patent—

The described wood stirrup *A*, consisting of the slat *a*, bent into the desired shape, and slotted in the direction of the grain of the wood, as at *d*, and of the roller or bar *b*, bolted to the 100 slat, said slat being bent to stand vertically where the cross-bar or roller *b* is connected or bolted thereto, substantially as set forth.

JAMES WOOLWORTH,
WILBER F. COWLES.
